UNITED STATES PATENT OFFICE.

WILHELM G. ALDEEN, OF ROCKFORD, ILLINOIS.

PHONOGRAPH OR LIKE CABINET.

Continuation of application Serial No. 319,350, filed August 23, 1919. This application filed June 16, 1921. Serial No. 478,219.

To all whom it may concern:

Be it known that I, WILHELM G. ALDEEN, a citizen of the United States, residing at Rockford, in the county of Winnebago and 5 State of Illinois, have invented certain new and useful Improvements in Phonograph or like Cabinets, of which the following is a specification.

The invention relates to cabinets for 10 phonographs and the like, and has for its general object the provision of an improved counter-balancing device for the cover or hood of the cabinet.

A more specific object of the invention 15 is to provide a counter-balancing device wherein a torsion spring is advantageously employed to resist the action of gravity, the device being substantially noiseless in operation, durable and otherwise of an efficient 20 and practical character.

Counter-balancing devices in common use in phonograph or like cabinets are of such character that as the hood approaches its lowermost position, the springs employed 25 are so tensioned that in spite of the increased pressure exerted thereon by the hood as it approaches the horizontal, the lifting effect of the springs is so increased that it becomes necessary for the operator or user 30 to take particular pains to see that the hood is in fact closed. The present invention aims to overcome this objection by providing a counter-balancing device which while capable of maintaining the hood in its 35 raised position will permit it to descend by gravity into closed position after having been moved substantially into such position.

Another object of the invention is to provide 40 a counter-balancing device which is capable of easy adjustment to vary the lifting or counter-balancing effect thereof.

Further object of the invention is to provide 45 a counter-balancing device of a practical character in that it is of comparatively simple construction and may be readily assembled.

The objects of the invention thus generally stated, together with other and ancillary advantages, may be obtained by the construction and arrangement illustrated in 50 the accompanying drawings forming part hereof in which Figure 1 is a vertical sectional view through the upper portion of a 55 phonograph cabinet, having my improved

counter-balancing device applied thereto, and showing the position of the parts when the hood is closed. Fig. 2 is a similar view but showing the position of the parts with the hood raised. Fig. 3 is an enlarged detail 60 view showing the counter-balancing means, the view being taken in the plane of line 3-3 of Fig. 5. Fig. 4 is a sectional view taken on the line 4-4 of Fig. 5 and showing the construction permitting the adjustment of the 65 counter-balancing spring. Fig. 5 is a horizontal sectional view on an enlarged scale, taken on line 5-5 of Fig. 1. Fig. 6 is a fragmentary elevation showing a detail of construction which facilitates the assembling 70 of the device. Fig. 7 is a sectional view taken on line 7-7 of Fig. 6.

While I have herein shown my invention as applied to a phonograph cabinet, it will be understood that the device is readily applicable to various types of cases or cabinets requiring counter-balancing devices, and although the invention is hereinafter described with considerable particularity, it is not to be limited thereby, in the interpretation of the appended claims, except as may be necessitated by the state of the prior art.

Referring to the drawings, 1 designates the main or base portion of a phonograph 85 cabinet having a hood 2 hinged at its rear edge as at 3. The base 1 of the cabinet is provided with the usual top wall 4, upon which the hood is adapted to rest when in closed position. The hood 2 is provided with 90 the usual bracket 5 to which is pivoted the upper end of a link 6 which depends through a slot 4a into the base and is operatively associated with the counter-balancing device indicated generally at 7, for supporting the 95 hood in raised position.

The counter-balancing means 7 comprises, in the present embodiment, a lever 8 pivoted at 9 upon a bracket 10 carried by the base 1. Herein said bracket is mounted upon 100 a base plate 11 of wood or the like, suitably secured to a side wall of the base, and the bracket is offset outwardly between its upper and lower ends, as at 12, so as to receive the rear end of the lever between it 105 and the base plate 11. The free end of the lever 8 is pivotally connected at 13 to the lower end of the link 6, and mounted on the lever near the free end thereof is a bracket 14 (Fig. 5) having a disk portion 110

- 15 spaced from the lever 8. Extending between said disk 15 and the lever 8 is a stud 16 having mounted thereon a coiled torsion spring 17.
- 5 The bracket 14 is secured to the lever 8 by means of a bolt 18, the bracket having edge flanges 19 for engaging the opposite edges of the lever 8 to prevent its rotation relative thereto. The portion 15 of the 10 bracket is in the form of a disk having a central opening therein for receiving the outer end of the stud 16, said stud being retained in position by suitable means such as a cotter-pin 20.
- 15 The spring 17 has its outer arm 21 held rigid with the disk 15 of the bracket, and the opposite or inner arm 22 of the spring is rigid with a rotatable element 23 journaled on the stud 16 between the lever 8 and the spring. In order to permit of the 20 adjustment of the spring to vary the torsion thereof, the disk 15 of the bracket is provided with an inwardly projecting flange 24 notched to provide a series of ratchet teeth 25 adapted to receive the arm 21 (Figs. 4 and 5). This construction permits of an 25 easy adjustment of the spring after the parts have been assembled. The opposite arm 22 of the spring may engage with a stud 26 on the rotatable element 23.
- In order to effect a rotation of the element 23 as the hood 2 of the cabinet is raised or lowered, and thereby unwind or wind up the spring 17, I herein provide 30 intermeshing teeth on the bracket 10 and rotary element 23 in the form of gear segments 27 and 28. To permit of the swinging movements of the lever 8 and at the same time guide it in such movements, the bracket 35 10 may be provided with an arcuate slot 29 in which a stud 30 mounted on the lever 8 and carrying a washer 30^a is arranged to operate.
- As the hood is swung upwardly upon its 40 hinge 3, the lever 8 is correspondingly swung upwardly on its pivot 9. In this operation the rotatable element 23 is rotated, by reason of the engagement of its gear segment 28 with the gear segment 27 of the bracket, to unwind the spring 17, upward movement of the hood being limited by a 45 finger 31 on the element 23 engaging with the bracket 14 (dotted lines Fig. 3).
- As the hood is swung downwardly, the 50 element 23 is actuated to wind up the spring 17, the tension gradually increasing as the hood moves toward the horizontal. The parts are so proportioned that as the hood approaches its closed position, the gear segment 55 28 of the element 23 disengages from the segment 27 of the bracket. In order that the increased tension upon the spring shall not operate to resist with increasing effectiveness the descent of the hood, the 60 segments 23 and 28 are formed with an eccentric pitch line so that the effective radius of the segment 23 gradually increases as the hood moves downwardly; and finally as the hood approaches its lowermost position the effective radius is suddenly increased to 70 a substantial length causing the hood to descend completely into its normal position upon the top 4 of the base. Upon the disengagement of the gear segments, the element 23 is held against rotation through 75 the action of the spring 17, by means of the finger 31 entering a notch 32 in the edge of the bracket below the segment 27, said finger being spaced a substantial distance from the nearest tooth of the gear segment 80 28 so as to permit of a complete disengagement of said segments.
- For the purpose of facilitating the assembling of the parts, the pivotal connection 13 between the link 6 and lever 8 is 85 made detachable. Herein for this purpose the pivotal stud is provided on its inner end with a pair of oppositely extending lugs 33 and the opening in the lower end of the link 6 is provided with diametrically extending notches 34. The lugs and notches are so arranged that when the link and lever are brought into alignment the parts may be assembled but when the parts are secured in position with the link and lever 90 out of alignment, said link and lever are held against detachment.
- It will be seen that I have provided a counter-balancing device for phonographs, which is of a very practical character. The 100 parts operate smoothly without perceptible noise, and the torsional spring is capable of very effectively counter-balancing the hood. Moreover, the arrangement of the gear segments to permit the hood to descend freely 105 as it approaches its horizontal position insures that the hood will remain closed when it is so desired. Should the spring become 110 worn or weakened in use, it may be very easily adjusted, and the difficulty commonly experienced in assembling disconnected parts of a device within the case is overcome by the detachable connection between the members secured to different parts of the cabinet.
- This application is a continuation of my 115 application Serial No. 319,350, filed August 23, 1919.
- I claim as my invention:
1. In a cabinet for phonographs or the like, the combination with a base having a hinged hood, of means for yieldingly supporting the hood in raised position comprising a member pivoted to the hood and depending into the base, a torsion spring, and means for effecting the winding and unwinding of said spring in the swinging movement of said hood including a pair of intermeshing gear segments one of which terminates in an elongated tooth adapted to 120 125 130

engage a notch formed in the other of said segments.

2. In a cabinet for phonographs or the like, comprising a base having a hinged hood, a pivoted member depending from the hood into the base, a torsion spring, and means arranged to be actuated by the movements of said hood to wind and unwind said spring, comprising a pair of intermeshing gear segments adapted as the hood approaches its closed position to disengage, and an elongated tooth carried by one of said segments arranged to abut the other of said segments at its terminus when said segments are disengaged and thereby diminish the lifting effect of said spring.

3. In a phonograph or like cabinet, the combination with a base having a hood, of a member pivoted to the hood and depending into the base, a lever pivoted in the base and pivotally connected to said member, a stationary gear element in the base, a rotary gear element mounted on said lever and meshing with the stationary gear element, said gear elements being formed with pitch lines eccentric to their centers, a torsion spring having one end fixed and the other end rotatable with said rotary gear element, and a finger on said rotary element adapted to engage with the stationary element to limit the rotation of said rotary element.

4. In a cabinet for phonographs or the like comprising a base having a hinged hood, a pivoted member depending from the hood into the base, a torsion spring, and means arranged to be actuated by the movements of said member in the swinging movements of the hood to wind and unwind said spring comprising a pair of intermeshing gear segments having eccentric pitch lines and adapted as the hood approaches its closed position to disengage, and a finger associated with one of said segments adapted to engage a notch in the other of said segments following the disengagement thereof to diminish thereby the lifting effect of said spring.

5. In a cabinet for phonographs or the like, the combination with a base having a hinged hood, of a member pivoted to the hood and depending into the base, a lever pivoted in the base and pivotally connected to said member, a bracket carried by said lever, a rotary element pivoted on the lever and having gear teeth thereon, a torsion spring having one end fixed to said bracket and the other end fixed to said rotary element, a second bracket mounted on the base and having a stationary gear element thereon with which the teeth of said rotary element are adapted to mesh, said gear elements being adapted to disengage as the hood approaches its closed position, and a finger on said element adapted to engage with the second bracket to prevent the un-

winding of the spring upon such disengagement, and also adapted to engage with the first mentioned bracket to limit upward swinging movement of the hood.

6. In a cabinet for phonographs and the like, comprising a base and a hinged hood, a member pivoted to the hood and depending into the base, a bracket mounted in the base and having a substantially upright gear segment thereon, a lever pivoted to said bracket and to said depending member for movement by the latter, a rotary element pivoted on said lever and having teeth arranged to mesh with said gear segment on the bracket and to disengage therefrom as the hood approaches its closed position, a torsion spring arranged to be wound and unwound in the rotation of said rotary element, and a finger on the rotary element spaced a substantial distance from the nearest tooth on said element, there being a notch in said bracket in which said finger engages after the teeth of the rotary element disengage from said gear segment.

7. In a phonograph or like cabinet, the combination with a base having a hinged hood, of counterbalancing means for the hood comprising a stationary gear element and a rotary gear element, means providing an abutment fixed with reference to said stationary element, said rotary gear element being adapted to operatively engage with said stationary gear element and having spring means associated therewith whereby to support the hood in raised position, said rotary element also having a part fixed with reference thereto and adapted to engage with said abutment, the distance between the axis of rotation of the rotary gear element and said abutment being greater than the distance between said axis and the stationary gear element.

8. In a phonograph or like cabinet, the combination of a base having a hinged hood, of means for counterbalancing the hood in raised position but allowing it to rest upon the base in its lowered position, said means including a stationary part having a gear segment, a rotary part also having a gear segment adapted to mesh with the first gear segment, spring means adapted to resist the rotation of said rotary part in the movement of the hood from its raised position toward its lowered position, and means for increasing the effectiveness of gravity acting upon said hood to rotate said rotary part against the action of said spring means when the hood approaches its lowered position, the last mentioned means including a member fixed with reference to the rotary part and adapted to engage with a shoulder fixed with reference to the stationary part when said gear segments are moved out of mesh with each other.

9. In a cabinet having a swinging hood,

means for counterbalancing the hood including a pair of intermeshing gear elements one of which is adapted to rotate in the movements of the hood, means adapted to resist the rotation of said rotary element in the downward movement of the hood, and means for increasing the effective radius of said rotary element whereby to increase the effectiveness of gravity acting upon said hood when the latter approaches its closed position.

10. In a phonograph or like cabinet, the

combination with a base and a hinged hood, of a member pivoted to the hood and depending into the base, a lever pivoted in the base and pivotally connected to said member, a torsion spring, and gear means operatively associated with said lever whereby to wind and unwind said spring in the swinging movements of the lever and limit said movements.

In testimony whereof, I have hereunto set my hand.

WILHELM G. ALDEEN.
